UNITED STATES PATENT OFFICE.

HERMANN BÜHRING, OF HANOVER, GERMANY.

CHRISTMAS-TREE CANDLE-HOLDER.

SPECIFICATION forming part of Letters Patent No. 790,556, dated May 23, 1905.

Application filed December 27, 1904. Serial No. 238,288.

To all whom it may concern:

Be it known that I, HERMANN BÜHRING, a citizen of Germany, residing at Hanover, Germany, have invented new and useful Improvements in Christmas-Tree Candle-Holders, of which the following is a specification.

This invention relates to a candle-holder of simple construction and designed to securely mount a candle upon a Christmas-tree branch or similar support.

In the accompanying drawings, Figure 1 is an end view of my improved Christmas-tree candle-holder; Fig. 2, a side view thereof; and Figs. 3 and 4 are end views of the holder, showing it mounted upon a thin and a thick branch, respectively.

The holder is composed of a resilient arched band or strap a, having disconnected ends. These ends are each turned inward to form hooks c, that are adapted to bite into the branch A, upon which the holder is mounted. Centered upon the convex back of the band a is an outwardly-projecting prong, socket, or similar device b for securing the candle to the band. 25

In use the band is sprung around the branch A, so as to straddle the same and cause the hooks c to enter the wood. With thin branches the band will contract, as in Fig. 3, while with thick branches it will expand, as in Fig. 4, the hooks c in both cases entering the wood and securely locking the holder to the branch.

What I claim is—

A Christmas-tree candle-holder composed of an arched resilient band having an inwardly-extending hook at each of its ends, and an outwardly-extending prong centered upon the convex back of the band, substantially as specified. 35

Signed by me at Hanover, Germany, this 13th day of December, 1904.

HERMANN BÜHRING.
